United States Patent Office

Des. 184,579
Patented Mar. 10, 1959

184,579

SINKER

Jack Platt, Winnipeg, Manitoba, Canada

Application May 12, 1958, Serial No. 50,831

Term of patent 14 years

(Cl. D31—4)

FIG 3

I claim:

The ornamental design for a sinker, as shown.
